ARC PREVENTION SYSTEM

Pierre Marie Gabriel Toulon, Paris, France, assignor to Products & Licensing Corporation, New York, N. Y., a corporation of Delaware

Application August 4, 1947, Serial No. 766,037
In France January 8, 1946

Section 1, Public Law 690, August 8, 1946
Patent expires January 8, 1966

13 Claims. (Cl. 175—294)

1

The present invention relates generally to a system for accomplishing sparkless commutation of electric currents, and more particularly to systems for making and breaking electric circuits, which may operate at high voltages and current intensities, without destructive sparking. The invention finds application in accomplishing sparkless commutation in rotary rectifiers and converters of the type which accomplish rapid commutation of circuits by means of mechanical circuit makers and breakers, or commutators, but the invention is not limited to such uses, and finds general application wherever a circuit must be opened, or closed, or opened and closed, or vice versa, in rapid succession.

It is a well known fact that commutation of electric current of considerable magnitude, and more particularly where high voltages are involved, presents problems of exceptional difficulty, because the sparking consequent on normal commutation effects rapid wear and destruction of the conductive contacts utilized to effect the commutation.

I have observed that the difficulties encountered in commutation are due to two primary phenomena. When a circuit is being closed by bringing into contact two metallic or other conductive contacts, the contacts become separated by a very small distance during the act of closure, and while separated by such a small distance, a high voltage exists between the contacts. The contacts are separated by air, or by some other gaseous dielectric, which is disrupted in response to the high voltage existing between the contacts, so that a small spark occurs between the contacts. If the current intensity in the spark is sufficiently great, intense ionization of the gaseous dielectric is caused, particularly if the contacts are subjected to local heating by the spark, and a disruptive arc discharge is initiated. This disruptive arc discharge is extremely destructive, especially if of considerable duration.

During opening of the contacts, the cross-section of the contacts which remain in contact during the opening process is progressively reduced, so that the current density in the contacts is correspondingly increased. This current density becomes so high, eventually, that some volatilization of the material of the contacts occurs, and some ionization of the gaseous dielectric adjacent to the contacts, so that eventually arc discharge is produced. This arc discharge is destructive of the contacts, and the destruction accomplished is higher the higher the current intensity, and the longer the duration of the arc,

2

In order to overcome the above recited difficulties, I make use of an auxiliary electric generator, using that word very broadly as implying any device in which a voltage may be generated.

- 5 I connect the auxiliary electric generator in series with the circuit to be commutated, and I so design the auxiliary electric generator that it is capable of generating an instantaneous electric voltage sufficiently great to counter-balance any potential difference existing between a pair of contacts which are about to come together to close an electric circuit, and I so select the polarity of that generator as to counter-balance that potential difference, thus bringing to zero, at the 10 moment of contact, the total voltage existing in the circuit. Thereby, current flow in the circuit is reduced to zero at the moment of contact, and circuit closure is accomplished without sparking or disruptive discharge of any character. In the 15 case of circuit opening the generated voltage reduces current flow across the contacts to zero, by reducing the voltage across the contacts to zero, or counter-balancing any voltage there existing.
- 20 25 Accomplishment of the process outlined in the previous paragraph involves the following steps or provision for accomplishing the following functions. In the first place it is necessary to measure the difference of potential which exists between a pair of contacts just prior to their coming into contact. In the second place I must provide means for measuring the intensity of current flowing between the contacts, precisely at the instant of their separation. I must provide a local 30 35 electrical generator, which is capable of providing a variable and controllable electromotive force over a period of time, and which is connected in series with the contacts which are to be separated or closed. I must further provide devices for controlling the local generator, for inserting in the circuit being commutated an appropriate voltage, of the precise magnitude and sense required for counter-balancing the 40 45 voltage existing between the contacts immediately prior to their closure, and for cancelling current flow in the contacts immediately prior to their opening.

Briefly described, and in accordance with the preferred embodiment of the present invention, 50 the local generator may take the form of an electric valve, having an appropriate energizing means, output circuit, and input circuit. The desired voltages for insertion in the commutated circuit may be generated in the output circuit 55 of the electronic valve, in response to control sig-

nals applied to its input circuit. More specifically the electronic valve may be constituted of a triode, the control grid which may be provided with control voltages of transient nature, during closure or opening of the commutating contacts, and the output circuit of which may comprise a transformer having a secondary winding connected in series with the circuit to be commutated, and a primary winding connected in series with the anode of the triode.

Voltages applied to the control electrode of the triode may be derived from impedances connected with the circuit to be commutated, via feed-back amplifiers. Accordingly, the triode forms one element of a feed-back loop, having both its starting and terminating points in the circuit to be commutated, and the loop is designed to be strongly degenerative, so that any condition found at the input of the loop tends to be annulled via the output of the loop.

My invention finds particular application to rotary commutators, in which case the circuits to be made and closed may be those between the copper segments of the commutator, and brushes, which may be metallic, but which if desired may be fabricated of other conductive material such as carbon.

I have found in practice that the principles of the present invention may be applied to rotary converter construction, where the voltages involved are of the order of several hundred kilo-volts, and wherein the powers to be commutated are of the order of several hundred thousand kilo-watts.

The present system has been found effective in practice, for extremely high potentials existent between adjacent segments of the commutator, for commutating power of extremely high orders, and regardless of the variations of load which may exist in the commutated circuit. The invention is extremely flexible in application, having been found extremely valuable for wide ranges of frequencies, regardless of the power factor of the energy which must be commutated, regardless of the number of interruptions which occur per second, and regardless of the mode of commutation, i. e., whether in response to rotating brushes and fixed commutator segments, or vice versa, and regardless of the speed of commutation.

It is accordingly a broad object of the present invention to provide a novel system of sparkless commutation.

It is a more specific object of the invention to provide a system for annulling the difference of voltage existing between a pair of contacts in process of closing.

It is another object of the invention to provide a system of commutation wherein the current flow between a pair of contacts in process of opening is annulled.

Still another object of the invention resides in the provision of a system of commutation wherein the voltage between a pair of contacts in process of closing is annulled during the closing process, and wherein the current flow between these contacts at the moment of opening is also annulled.

It is a more specific object of the present invention to provide a system of sparkless commutation wherein voltage across a pair of contacts is annulled while the contacts are closing and wherein current flow between the contacts is annulled while the contacts are opening, and wherein the annulment of both voltage and current

is accomplished by means of a degenerative feed-back loop having both an input and an output connected in the circuit being commutated, and in series with the contacts.

Still another object of the present invention resides in the provision of a system for continually measuring the voltage existent across a pair of contacts in process of closing, and the current flowing between a pair of contacts in process of opening, for utilizing these measurements to introduce into the circuit containing the contacts an opposing voltage sufficient in magnitude at all instants of time, and of proper polarity, to counter-balance the measured voltage, and to annul the flow of current.

The above and still further features, objects, and advantages of the invention will become apparent upon consideration of the following detailed disclosure of a specific embodiment thereof, especially when taken in conjunction with the accompanying drawings, wherein:

Figure 1 is a schematic circuit diagram of a preferred embodiment of the invention; and

Figure 2 is a timing diagram showing various conditions of voltage and current existing in a circuit subject to closure and opening, in accordance with the invention.

Referring now more specifically to the accompanying drawings, the reference numeral 201 indicates an input circuit, which provides power to be commutated, and then to be delivered to an output circuit 202. The input circuit 201 may, for example, be an alternating current circuit, and the output circuit 202 a D. C. circuit, the function of the commutation being to rectify the alternating current, and to deliver to the output circuit 202 a rectified direct current. On the other hand, the invention is by no means limited to this application, and may be applied, for example, to the conversion of frequency, in which case the output circuit 202 may be a load circuit for the input 201, wherein flows current of alternating nature, at a different frequency than flows in the input 201. The invention also finds application to the conversion of direct current into alternating current, in which case the input circuit may be a D. C. circuit and the output circuit an A. C. circuit, conversion being accomplished by means of the commutation process.

Commutation is accomplished by means of a brush 203, assumed to be rotating with respect to a commutator segment 204. Rotation of the brush may be accomplished in response to rotation of a motor 205, which is energized from a source of power conventionally illustrated as a battery 220, when the switch 221 is closed. Suitable means are provided, which are not illustrated in order that the circuit diagram may not be unduly complicated, and in order better to illustrate the basic principle of the invention, for bringing the brush 203 into contact with the commutator segment 204 precisely at the time assigned for closure of the circuit between the input 201 and the output 202, and for providing that the brush 203 will leave the segment 204 at the time assigned for opening of the circuit.

The problem presented is, then, that of annulling the voltage existing between the brush 203 and the commutator segment 204 just as these elements come into contact, and for annulling current flow between the commutator segments 203, 204, just as these elements break circuit; and this regardless of the precise con-

tent of the voltage or current, or of their variations with time, or of the speed of relative motions of the brush 203 and the commutator 204.

In accordance with the invention, I connect in series with the brush 203 a resistance 206 and a winding or coil 207, the latter constituting the secondary winding of a transformer having a primary winding 208. The voltage across the resistance 206 is then a precise replica of the current flowing in the commutated circuit.

I further provide an auxiliary commutator segment 214 and an associated brush 215, the commutator segment 214 being connected directly to the commutator segment 204, and the brush 215 being driven in synchronism with the brush 203 by the motor 205, except for a small relative angular displacement between the brushes 203 and 215, the brush 215 being slightly in advance, so that the brush 215 comes into contact with the segment 214 slightly before the brush 203 comes into contact with the segment 204. In series with the brush 215 is connected two high resistances in series, designated by the reference numerals 216 and 217, values being selected sufficiently high to permit the passage of current of very low intensity only, in order that no spark formation may be permitted between the brush 215 and the segment 214, and further in order that the voltage across the resistance 216 shall be a precise replica of the voltage existing between the brush 215 and the segment 214 and consequently between the brush 203 and the segment 204.

The voltage existing across the resistance 206 is applied to the input of the amplifier 218, while the voltage existing across the resistance 216 is applied to the input of the amplifier 219.

There is additionally provided a triode 210, capable of delivering extremely high power for short intervals of time, triode 210 having in its output or anode circuit the primary winding 208, and having its cathode connected to one output lead of the amplifier 218, and to one terminal of the resistance 216, the cathode being then considered a reference or ground point for the system.

The output of the amplifier 218 is connected to a commutator segment 213, while the output of the amplifier 219 is connected to a commutator segment 212. A brush, driven in synchronism with the brushes 203 and 215 sweeps over these contacts in sequence, being driven by the motor 205. This brush is connected to the control electrode 211 of the triode 210, and consequently applies as a control voltage to that control electrode, in sequence, the outputs of the amplifiers 218 and 219, which are representative respectively of current flowing in the commutated circuit between input 201 and output 202, and voltage across the brush and commutator segment 203, 204, in series with the commutated circuit.

If the time constants of the various parts of the feed-back loop are sufficiently low, and suitably selected, the reaction of the triode 210 is practically instantaneous, and if the amplification provided by the amplifiers 218 and 219 is sufficient, the current flowing in the resistance 206 is reduced to zero, or substantially to zero, as contact between the brush 203 and the commutator segment 204 is made, and the current flowing in the resistance 206 is reduced to zero at the time that the contact between the brush 203 and the commutator segment 204 is being

broken. To this end the application of control voltage to the triode 210 from the contacts 212 and 213 is suitably timed, so that the contact at 212 is connected to the control electrode of the triode 210 during the circuit closing time, and so that the contact 213 is connected to the control electrode of the triode 210 during circuit opening time.

The operation of the present system is now described by reference to Figures 1 and 2 of the accompanying drawings. For the purpose of this explanation it is assumed that the following sequence of operations occurs. First occurs closure of the contacts 203, 204, between which exists a predetermined initial voltage V_1 . Thereafter is accomplished opening of the contacts 203, 204, in the presence of a current i therebetween. It is a function of the present system to annul the voltage V_1 , and the current i , by means of a negative feed-back loop.

The upper horizontal line of Figure 2 illustrates as a timing diagram, the operations which occur in the system starting with an open circuit, and terminating with an open circuit, with an intermediate circuit closure. It is assumed that at point 23 of the first horizontal line of Figure 2, open circuit conditions exist, and that the voltage of the input circuit 201 is not equal to the voltage of the output circuit 202, so that upon making contact between brush 203 and commutator segment 204 the risk of starting destructive spark and arc discharge exist. The voltage V_1 is assumed to be the voltage between the brush 203 and commutator segment 204 at this instant of time, and is plotted below point 23 on the lowermost line of Figure 2.

Point 24 of Figure 2 corresponds to a time which just precedes closure of the contacts 212, at which time it may be assumed that some predetermined D. C. current flows in the triode 210.

Point 25 corresponds with the time at which the brush 215 just begins to contact commutator segment 214, so that the voltage applied to the input of the amplifier 219 represents the voltage existing between the brush 203 and the commutator segment 204, just as circuit closure occurs. The output of the amplifier 219 is now applied via contact 212 to the control electrode of the triode 210, and the negative feed-back loop is effectively placed in action, to generate a voltage in the secondary winding 207, which is just adequate to balance out the voltage existing between brush 203 and commutator segment 204. At the time 27 the main contacts 203, 204 close, and shortly thereafter, i. e. at time 28, the contact 212 is interrupted, breaking the negative feed-back loop. The latter remains broken while the contacts 203, 204 are in intimate contact, and consequently while current is passing between the input 201 and the output 202.

The point 29 on the graph represents then a time in an interval which lasts as long as the circuit is closed. This time is assumed to expire at the point 30, at which time the brush 203 is in process of proceeding out of contact with the commutator segment 204. It is precisely at this time that the contact 213 is placed in circuit with the control electrode of the triode 210, whereby the triode 210 is controlled in response to the output of the amplifier 218, which passes a current determined by current flow in the circuit between input 201 and output 202, as measured across resistance 206. Con-

nection of contact 213 to the control electrode of triode 210 establishes the required feed-back loop, in readiness for an annulling action, and at point 31 a separation of the contacts 203, 204 commences, the contacts being completely broken at point 33. At point 34, the contact 213 is completely open and the feed-back loop is dis-established.

Figure 2 may be examined from another point of view. The first line of this figure provides a time sequence, when certain circuit closure and opening operations take place. The second line illustrates the values, as a time function, of the small control current which flows in the auxiliary contacts 214, 215, and in the resistances 216, 217, and which are representative of voltage between the main commutator contacts 203, 204. That current starts at point 25, and it assumes at first a high value, due to the high value of the voltage across the contacts 203, 204. Thereafter, however, due to the negative feed-back of voltage introduced in the secondary winding 207, by the negative feed-back loop, this voltage is reduced radically, and eventually falls substantially to zero when the brush 203 comes into full contact with the commutator segment 204, at point 27.

The third line of Figure 2 represents the variations as a function of time of current intensity in the main circuit as measured in terms of voltage across the resistance 205. That current starts only after the contact between brush 203 and commutator segment 204 has been completed, i. e. at point 27, and at time 28 has risen to its maximum value, returning sometime thereafter to its normal value represented by I.

The fourth line of Figure 2 represents variations in output current of triode 210 as a function of time. Prior to time 24, the triode 210 is not operative, since the feed-back loop of which it forms a part is not completed. During the period 24 to 25, triode current is initiated, and is at first at a very low value. Triode current increases rather rapidly, so that the rate of change of triode current has an appreciable value, the voltage induced in the secondary winding 207 being proportionable to this rate of change. The rate of change is so established by the feed-back loop that the total voltage between brush 203 and commutator segment 204 is maintained substantially at zero value. When the contacts 212 are opened, however, the variation of current in the feed-back loops ceases progressively, so that the effect of the feedback loop is destroyed, and the current flowing between the brush 203 and the commutator segment 204 is determined solely by the relation between the input 291 and the output 292.

In order to open the main circuit, which begins to occur at the time 30, the negative feed-back loop is placed in operation via the contact 213, which causes automatically first a rapid increase and then a decrease in current in the triode, i. e. a negative slope for the variation of current

$$\frac{di}{dt}$$

This rate of decrease assumes such a value that the current in the main circuit falls almost to zero. When the contact 213 opens entirely, the triode 210 is removed from the feed-back loop, disabling the latter, which causes the appearance of a voltage between the brushes 203, 204.

Since, however, this voltage occurs only at an appreciable time after the separation of the contacts, the contacts have had time to separate sufficiently so that the voltage has no deleterious effect, is not capable of sparking or arcing, and can remain at any value desired.

The fifth line of Figure 2 represents the voltage generated in the secondary winding 207, as a function of time. At the time of contact closure, 10 between brush 203 and segment 204, a voltage appears in the secondary winding 207, signalling that the negative feed-back loop has commenced action. This voltage rapidly attains a value such that the voltage existent between the brush 203 and the contact 204 is substantially zero, after which time the voltage generated in the secondary winding 207 can change without deleterious effect to the operation of the system, even to the extent of change in sign, after time 15 28. During opening of the main circuit, again 20 the voltage supplied by the negative feedback loop assumes continuously a value such as to reduce the current in the main circuit to zero, until the brushes have separated. After separation 25 of the brush 203 and the commutator segment 204, the voltage at the terminals of secondary winding 207 can assume any value whatsoever, but will eventually fall to zero, when the contact 213 is broken, removing the negative 30 feed-back loop from operation.

While I have described and illustrated one specific example of the present invention it will be clear to those skilled in the art that variations of the specific arrangement adopted, and 35 of its details, may be resorted to without departing from the true spirit of the invention as defined in the appended claims.

What I claim is:

1. A system of sparkless commutation comprising: means for measuring the potential existing 40 between two commutating contacts connected in a current carrying circuit only while said contacts are closing, said contacts when closed serving to complete said circuit, a feedback amplifier having an input circuit and an output circuit, means for applying said potential to said input circuit, means for coupling voltage deriving from said output circuit in series with said current carrying circuit for opposing said difference of potential 45 only while said contacts are closing, and means for thereafter closing said contacts and for reducing to zero said voltage deriving from said output circuit after said contacts have been closed.

2. A system of sparkless commutation comprising: means for measuring the current flowing 50 between a pair of commutating contacts connected in a current carrying circuit only while said contacts are in process of opening, said contacts when closed serving to complete said circuit, a feedback amplifier having an input circuit and an output circuit, means for applying to said input circuit a potential proportional to said current flowing between said pair of contacts only 55 while said contacts are in process of opening, means for coupling voltage deriving from said output circuit in series with said current carrying circuit for reducing said current flowing between said commutating contacts, and means for thereafter opening said commutating contacts and for reducing to zero said voltage deriving from said output circuit.

3. A system of sparkless make and break of a pair of contacts connected in series with a current carrying electric circuit comprising: an

amplifier having an output circuit and an input circuit, means for coupling said output circuit in voltage reducing relation with said electric circuit, and means coupling said input circuit with said electric circuit for applying to said amplifier for amplification thereby a voltage proportional to current flowing in said electric circuit.

4. In a system of sparkless commutation, a pair of commutating contacts connected in an electric circuit, an electronic control valve having an anode, a cathode and a control electrode, a transformer having a primary and a secondary winding, means for connecting said primary winding of said transformer between said anode and cathode, means for connecting said secondary winding in series with said contacts in said circuit, means for applying between said grid and said cathode a potential varying as a function of potential between said contacts only while said contacts are in process of closing, and means for applying, between said grid and said cathode only while said contacts are opening a further potential varying as a function of current flowing between said contacts.

5. A system of sparkless make and break of a pair of contacts connected in series with a current carrying electric circuit comprising: an amplifier having an output circuit coupled in voltage inducing relation with said electric circuit, said amplifier further comprising an input circuit coupled to said electric circuit for applying to said amplifier for amplification thereby a voltage proportional to the potential difference between said contacts.

6. A system of sparkless make and break of a pair of contacts connected in series with a current carrying electric circuit comprising: an amplifier having an output circuit coupled in voltage inducing relation with said electric circuit, said amplifier further comprising an input circuit coupled to said electric circuit for applying to said amplifier for amplification thereby a voltage proportional to the current flowing between said pair of contacts.

7. In a system of commutation for making and then breaking a current carrying circuit: means for deriving the potential existing between two commutating contacts connected in said current carrying circuit only while said contacts are closing, said contacts when closed serving to complete said circuit, a feedback amplifier having an input circuit and an output circuit, means for applying said potential to said input circuit, means for coupling voltage deriving from said output circuit in series with said current carrying circuit for opposing said difference of potential and for reducing said difference of potential substantially to zero only while said contacts are closing, and means for thereafter closing said contact and for reducing said voltage deriving from said output circuit to zero after said contacts have been closed, means for measuring the current flowing between said pair of commutating contacts only while said contacts are in process of opening, a further feedback amplifier having an input circuit and an output circuit, means for applying to said input circuit of said further feedback amplifier a potential proportional to said current flowing between said pair of contacts while said contacts are in process of opening, means for coupling voltage derived from said output circuit of said further feedback amplifier in series with said current carrying circuit for reducing said current flowing between

said commutating contacts substantially to zero while said contacts are in process of opening, and means for reducing to zero said voltage deriving from said output circuit after said commutating contacts have opened.

8. A system of sparkless commutation comprising: means for measuring the potential existing between two commutating contacts connected in a current carrying circuit only while said contacts are closing, said contacts when closed serving to complete said circuit, said means for measuring comprising an auxiliary contact connected to one of said two commutating contacts via a high resistance, a feed-back amplifier having an input circuit and an output circuit, means for connecting said auxiliary contact to said input circuit to supply control potential to said input circuit, means for coupling voltage deriving from said output circuit in series with said current carrying circuit for opposing said difference of potential only while said contacts are closing, and means for thereafter closing said contacts and for reducing to zero said voltage deriving from said output circuit after said contacts have been closed.

9. A system of commutation of electric currents in an electric circuit by means of at least one brush and a plurality of commutator segments, comprising, first means for reducing to zero the voltage across said contacts only while said contacts are in process of closing by introducing in said electric circuit only while said contacts are closing a time varying voltage continuously equal and opposite to said first voltage, second means for deriving said time varying voltage in response to a continuous measurement, while said contacts are closing, of resultant voltage across said contacts, third means for reducing to zero the current flowing between said contacts while said contacts are in process of opening by introducing in said electric circuit, only while said contacts are in process of opening, a further time varying voltage continuously adjusted in amplitude in response to a continuous measurement of said current while said contacts are opening to reduce said current substantially to zero, and mechanical switch means for synchronizing the times of operation of said first and third means with respect to relative motion of said at least one brush and said plurality of commutator segments.

10. A system of commutation of electric currents in an electric circuit by means of at least one brush and a plurality of commutator segments, comprising, first means for reducing to zero the voltage across said contacts only while said contacts are in process of closing by introducing in said electric circuit only while said contacts are closing a time varying voltage continuously equal and opposite to said first voltage, second means for deriving said time varying voltage in response to a continuous measurement, while said contacts are closing, of resultant voltage across said contacts, third means for reducing to zero the current flowing between said contacts while said contacts are in process of opening by introducing in said electric circuit, only while said contacts are in process of opening, a further time varying voltage continuously adjusted in amplitude in response to a continuous measurement of said current while said contacts are opening to reduce said current substantially to zero, and electronic switching means for synchronizing the times of operation of said first and third means with respect to relative motion

of said at least one brush and said plurality of commutator segments.

11. In a system of sparkless commutation, a first commutator segment, a second commutator segment, means for synchronously moving said commutator segments, a resistance interconnecting said commutator segments, a main current carrying brush contacting said first commutating segment, an auxiliary brush adjacent said main current carrying brush and contacting said first commutating segment, a relatively high resistance interconnecting said main current carrying brush and said auxiliary brush, a transformer secondary winding having a first terminal, a low resistance connecting said current carrying brush to said first terminal, an electronic tube having an anode, a cathode and a control electrode, a primary winding for said transformer secondary winding and a source of anode voltage connected in series between said anode and cathode, an electrode only capacitively coupled with said second commutator segment, a resistance for connecting said electrode to said first terminal, a selector switch having a plurality of contacts and a selector arm, a first lead connecting one of said contacts with said first terminal, a second lead connecting another of said contacts with said auxiliary brush, a third lead connecting still another of said contacts to said electrode, means coupling said selector arm with said control electrode, and means controlling motion of said selector arm relative to said contacts to provide contact between said selector arm with said one of said contacts while said main current carrying brush and said first commutating segment are in process of breaking contact, and to provide contact between said selector arm and another of said contacts while said current carrying brush and said first commutating segment are in process of making contact.

12. In a system of sparkless commutation, a first commutator segment, a second commutator segment, means for synchronously moving said commutator segments, a resistance interconnecting said commutator segments, a main current carrying brush contacting said first commutating segment, an auxiliary brush adjacent said main current carrying brush and contacting said first commutating segment, a relatively high re-

sistance interconnecting said main current carrying brush and said auxiliary brush, a transformer secondary winding having a first terminal, a low resistance connecting said current carrying brush to said first terminal, an electronic tube having an anode, a cathode and a control electrode, a primary winding for said transformer secondary winding and a source of anode voltage connected in series between said anode and cathode, an electrode only capacitively coupled with said second commutator segment, means for connecting said electrode to said first terminal, a plurality of electronic switching channels, each of said channels having an output circuit, means coupling all said output circuits in control relation to said control electrode, each of said plurality of electronic switching channels further comprising a separate electronic tube having a first and a second control grid, means for applying sequential on-switching voltages to said first control grids, means for connecting one of said second control grids to said auxiliary brush, means for connecting another of said second control electrodes to said first terminal, and means for synchronizing said on-switching voltages with relative motion of said commutator segments.

13. In a system of sparkless commutation, a pair of commutating contacts connected in an electric circuit, an electronic control valve having an anode, a cathode and a control electrode, a transformer having a primary and a secondary winding, means for connecting said primary winding of said transformer between said anode and cathode, means for connecting said secondary winding in series with said contacts in said circuit, means comprising an electronic switching tube for applying between said grid and said cathode a potential varying as a function of potential between said contacts only while said contacts are in process of closing, and means comprising a further electronic switching tube for applying between said grid and said cathode only while said contacts are opening a further potential varying as a function of current flowing between said contacts.
